UNITED STATES PATENT OFFICE.

HERMAN B. LERMER, OF NEWARK, NEW JERSEY, ASSIGNOR TO HYGIENIC TUBE CO.,
OF NEWARK, NEW JERSEY, A CORPORATION OF NEW JERSEY.

CONTAINER.

Application filed April 20, 1926. Serial No. 103,208.

This invention relates to containers and particularly to such as are used for liquids, powders and pharmaceuticals in general.

One object of the invention is to provide 5 a container of unitary construction having impermeable walls, air, gas and moisture proof.

A further feature is in the provision of 10 a container the walls of which are transparent and substantially unbreakable due to their yielding nature, and provided with bands susceptible of receiving inscriptions in addition to other bands bearing permanent legends.

15 Another aim is to produce effective means for closing the container by impervious caps, removable and replaceable at will.

These and similar features, which will become apparent as the description progresses, are accomplished by the novel construction of parts hereinafter described in detail and illustrated in the drawing constituting a component of this disclosure, and in which:—

25 Figure 1 is a partial side elevational, partial longitudinal sectional view of an embodiment of the invention.

Figure 2 is a transverse sectional view taken on line 2—2 of Fig. 1.

30 Figure 3 is a side view of the upper part of a container showing a modified type of closure.

Figure 4 is a similar view showing a further modification.

35 Figure 5 is another like view of a variant closure as applied.

Figure 6 is a similar view of a still further variation of closing means.

The container as shown consists of a body 40 10, here shown as cylindrical, having a flanged base 11 extending slightly outward beyond the periphery of the body wall, presenting a flat level surface by which the container is held erect when disposed on a level surface.

45 It is to be noted that the flange 11 is formed integral with the body wall 10 by doubling the material, folding it tightly upon itself, and thereafter shaping the inner edge into an arcuately raised bottom 12, all of unitary construction.

It will be obvious that the flanged edge acts very materially to re-enforce the structure, the body wall 10 of which is flexible 55 to a limited extent.

As shown in Fig. 1, the upper edge of the container is curled to constitute a bead 13, acting as a re-enforcement and producing a desirable edge finish, the bead being 60 presented outwardly to admit the entrance of an ordinary cork stopper 14.

In place of the beading at the upper edge, a coarse pitch screw thread 15 may be formed on the upper portion of the container to be engaged with corresponding threads 65 on the flange 16 of a cap 17, as seen in Figure 3, thus constituting a well known form of cap closure, the combined threads operating, in conjunction with the cap, to stiffen the structure and make a tight joint. 70

In Figure 4 the top of the container is plainly cylindrical and set therein is a ring 75 18 of celluloid or even metal, the same being securely held by contraction of the container wall in the process of hardening or curing that takes place.

The upper portion of the ring 18 is provided with threads to engage the flange 19 of a cap 20 in the manner previously indicated.

80 A similar ring or band 21 is shown inserted in Fig. 5, the upper extending portion 22 of the band being slightly tapered or conical to be engaged by a plain flange 23 formed with a cap 24 thus being held frictionally tight by a wringing movement as will be apparent.

85 The modification, shown in Figure 6, is quite similar, the same consisting of a ring 25 having a slightly flaring outstanding portion 26 adapted to receive a cork or rubber stopper 27 as will be apparent.

90 A band 28 having an opaque, white or colored surface is applied to the containers, the same presenting a space on which an inscription may be made and a similar band 29 may bear the imprint of the manufacturer or dealer.

95 These bands may either completely or partially encircle the body and are applied 100 in the manner of an enamel to become a part of the body, not as a removable label but part of the structure.

105 It will be understood that the so called bands may be applied in various shapes and in any position, not necessarily as shown, and the operation and use of the containers will be clearly evident.

110 Although the foregoing is descriptive of the preferred embodiment of the invention,

it will be apparent that minor changes may be made in its construction, without the exercise of invention or conflicting with the scope of the claims hereto appended.

5 Having thus described my invention, what I claim as new and desire to secure by Letters Patent, is:—

1. A flexible container comprising a flexible transparent body composed of impervious material, a bottom integral with said body, a re-enforcing means at the top and bottom of the body, a cover engageable on the body, and enamel annular strips baked directly on said body, one of said

strips being adapted to carry a permanent 15 imprint and others to receive an inscription.

2. A container comprising a hollow drawn cylindrical body having a beaded top, a beaded base and an arcuately raised bottom all of unitary construction and composed of transparent impervious material capable of flexing without fracture, the main portions of said body having a polish finish incapable of receiving inscriptions, and zones on said body suited to receive inscriptions. 20 25

This specification signed and witnessed this 17th day of April, 1926.

HERMAN B. LERMER.
